CLAIM

An ornamental design for a label printer, as shown and described.

DESCRIPTION

FIG. 1 is a perspective view showing our new design for a label printer.

FIG. 2 is a front elevational view thereof;

FIG. 3 is a left elevational view thereof;

FIG. 4 is a right elevational view thereof;

FIG. 5 is a top plan view thereof; and,

FIG. 6 is a rear elevational view thereof.

The broken lines shown in all figures are for illustrative environmental purposes only and form no part of the claimed design. The broken lines which define the bounds of the claimed design form no part thereof.
